FINISHING MACHINE

John W. Thieme, West Compton, and Patrick J. McDonnell, Compton, Calif.; said Patrick J. McDonnell, assignor to said John W. Thieme

Application June 27, 1955, Serial No. 518,088

13 Claims. (Cl. 94—45)

The invention relates to machinery for working soft concrete and has particular reference to a rotary machine power operated and manipulated by hand by use of which poured concrete can be troweled and later finished by use of the same machine adjusted in an appropriate manner.

Up until a few years ago almost all concrete was finished by hand. The laying of concrete roadways later gave rise to use of power operated equipment for screeding the surface of the roadway but even here final troweling and finishing up until relatively recent times has been done by hand.

It has been learned through studies with respect to hand labor methods, particularly where the hand labor work is of a heavy character such as is the troweling and finishing of concrete slabs, that a tremendous amount of time may be needed for such operations to the point where the expense of troweling and finishing considerably overbalances the cost of material and other operations in connection with the laying of the slab. These circumstances have given rise to the design and construction of a certain line of power operated concrete surfacing machinery which has resulted in the placing upon the market of some four or five rotary actuated finishing machines wherein the blades are driven usually by a gasoline engine and the machine manipulated over the slab by hand. These machines have followed a substantially uniform pattern in that they have comprised a carriage on which is mounted a small, low horse-power, gasoline engine below which is a housing or rotating head. On the head are radially extending blades, the blades being so mounted that they can be tiltably adjusted in order to produce a greater or lesser degree of working of the soft concrete, depending upon what surfacing operation is desired by the installer.

Another common feature of such machines is the employment of a rather simple, conventional clutch arrangement designed to take hold to a greater or lesser degree depending upon the speed of operation of the power unit. Hence, the expedient has been to provide a throttle control adapted to be manipulated by the operator so that by opening or closing the throttle and hence varying the speed of the engine, the speed of rotation of the blades can be controlled. A serious disadvantage of this type of device is that the gas engine can never be started unless an assistant operator holds the handle by which the device is manipulated since otherwise as soon as the engine is started the handle will begin to whip around while the blades remain fixed in position upon the concrete. The same disadvantage follows through in operation of the device under those circumstances wherein should an obstruction be hit and the operator lose his grip upon the handle, the blades will set themselves in the concrete and the handle will whip around until some obstruction is thrown in its way to stall operation of the engine.

Another and serious disadvantage in machines heretofore placed upon the market is an open construction of

2

the operative parts which permits wet concrete to lodge in many different places wherein unless completely and thoroughly washed the concrete tends to set, gradually accumulating and clogging the machinery as well as adding its weight to the normal weight of the machine. In addition to the clogging the action of concrete in setting up has had a serious deteriorating effect upon those portions of the mechanism which have been exposed.

In devices of the prior art guards have of necessity been provided enclosing the area within which the troweling blades rotate. This has been essential for safety purposes. In most instances the guards thus provided have been employed as a tilting support for the outer ends of the blades. Although constructed in this fashion the guard serves its purpose as a guard, nevertheless, by reason of the fact that it must rotate as the blades rotate, the guard itself has a tendency to climb upon obstructions and form work near edges of slabs being worked upon and has been very prone to throw the entire machine out of alignment creating often a dangerous condition when a rotary surfacing machine at full speed chances to climb up on the form work.

Although numerous attempts have been made by the prior art to provide a ready means of changing the tilt adjustment of the blades thereby to increase or diminish friction of the blade on the soft concrete and its ability to work the surface of the concrete, such adjustments have often been designed in such fashion that they can be made only when the machine is stopped and in those few occasions where the adjustment is attempted as an adjustment operable while the machine is in operation, the adjustments have been awkward, undependable, and difficult for the average operator to control to the degree necessary to perform an effective job.

It is therefore among the objects of the invention to provide a new and improved rotary surfacing machine for material such as poured concrete which is highly effective in its operation and which has built into it a combination of features making it safe to operate and making it one capable of manipulation without undue fatigue to the operator.

Another object of the invention is to provide a new and improved rotary concrete surfacing machine which is compact in its design and construction to the end that virtually all moving elements are housing or concealed and thus protected from the action of wet concrete making the device one easy to clean and easy to maintain in proper working condition and with a greater safety factor for the operator.

Still another object of the invention is to provide a new and improved rotary concrete surfacing machine constructed in a manner such that the gear train and a power means for adjusting the blades are mounted and housed in a hermetically sealed casing wherein lubricant for the gear train is employed simultaneously as a hydraulic fluid adapted when desired to be sent to a hydraulic motor for adjusting the blades and which when not used for that purpose can be readily by-passed without loss of efficiency to continue its function as a gear lubricant.

Still another object of the invention is to provide a new and improved power means for adjusting the tilt of the blades in a concrete rotary surfacing machine, which power means is manipulated by hydraulic pressure generated as long as a source of power is in operation, the hydraulic means being so arranged that it can be manipulated from the ends of the handle by fingertip control.

Further among the objects of the invention is to provide 70 a new and improved power actuated manually manipulatable concrete surfacing machine suitably provided with stationary guards collapsible for easy shipping and which

are to a great degree safety factors, the invention having for its object to further provide an adjustable handle control which can be manipulated at any time, whether the machine is in operation or not, from a free end of the handle, the adjustment of handle height being conveniently mounted also with relation to a throttle control and a control for the blade adjustment so that the operator has complete control over the machine from the handle at all times.

Still another object of the invention is to provide a new and safer clutch control that does not depend on varying engine speeds to control rotation of the blades, and that automatically disengages should the operator let go or lose control of the handle while operating the machine.

With these and other objects in view, the invention consists in the construction, arrangement and combination of the various parts of the device whereby the objects contemplated are attained, as hereinafter set forth, pointed out in the appended claims and illustrated in the accompanying drawings.

In the drawings:

Figure 1 is a vertical sectional view of the device.

Figure 2 is a fragmentary sectional view on the line 2—2 of Figure 1.

Figure 3 is a cross-sectional view of the device taken on the line 3—3 of Figure 1.

Figure 4 is a view illustrating in detail the hydraulic circuit with the hydraulic pump shown partially in section and showing adjacent portions of the machine in phantom view.

Figure 5 is a view partially in section showing details of the hydraulic valve taken on the line 5—5 of Figure 4 and details of the manual adjustment of the hydraulic valve which exists at the outer end of the handle.

Figure 6 is a longitudinal sectional view of the hydraulic motor for operating the blade adjustment taken on the line 6—6 of Figure 4.

Figure 7 is a fragmentary sectional view of a portion of the hydraulic pump taken on the line 7—7 of Figure 4.

Figure 8 is a cross-sectional view taken on the line 8—8 of Figure 1 showing the several controls at the end of the handle.

Figure 9 is a sectional view taken on the line 9—9 of Figure 8 showing further details of the control and particularly the clutch control.

Figure 10 is an elevational view partially in section showing a modified type of drive mechanism.

Figure 11 is a sectional view showing a modified form of hydraulic means for hand manipulation to adjust the tilt of the blades.

Figure 12 is a longitudinal sectional view taken on the line 12—12 of Figure 11 showing valving of the manually actuated hydraulic adjusting means.

In an embodiment of the invention chosen for the purpose of illustration there is shown a rotary concrete surfacing machine comprising a casing indicated generally by the reference character 10, a conventional power source 11, the base of which is shown mounted on the casing 10, a housing 12 below the casing and adapted to carry blade assemblies 13, 14 and 15, and a handle assembly 16. A ring guard 17 is mounted upon legs 18, 19, 20 and 21 to support the guard in a position below the casing 10 and surrounding the outermost ends of the blades.

As suggested in Figure 3 the guard may be built in two semi-circular halves joined by a bar 54. A rivet 55 secures the bar to one half and a removable pin 56 secures the bar to the other half.

More particularly the casing consists of an upper half 22 and a lower half 23 hermetically sealed at their opposing edges and adapted to be bolted together by means of a number of appropriately spaced bolts 24, one of which is shown in Figure 1 passing from the upper half 22 into the lower half 23. The upper and lower half of the casing when bolted together form a chamber 25. A conven-

tional power source 11 may, for example, be a low horse-power gasoline engine of the type currently employed on a great variety of small hand manipulated but power actuated mobile tools. The power source is equipped with a drive shaft 26 which extends downwardly through a field passage 27 into the chamber 25.

In the embodiment illustrated in Figure 1 a pinion 28 is non-rotatably secured to the drive shaft 26 by the aid of a key 29 so that the pinion rotates with the drive shaft. The pinion meshes with and is adapted to drive a large gear 30. The large gear is mounted upon a gear shaft 31, the shaft being mounted by means of a bearing 32 in the upper half 22 of the casing and by means of a bearing 33 in the lower half 23 of the casing. In the embodiment shown the large gear 30 is free to move with respect to the gear shaft 31, the gear being one provided on its lower side with a clutch indicated generally by the reference character 35.

By way of example only the clutch 35 is shown as a cone clutch with a cone clutch face 36 forming the inside face of a clutch wall 37 and the cone clutch element 38 being adapted to enter the cone clutch face by movement upwardly.

The cone clutch element is non-rotatably secured to the gear shaft 31 by means of a key 39 so that when the cone clutch element is rotated the gear shaft 31 rotates and causes a pinion 40 to rotate because of the pinion being non-rotatably secured to the gear shaft by means of a key 41. The pinion in turn meshes with a gear 42 of large circumference. The gear 42 as well as the pinion 40 lies in a well 43 at the bottom of the chamber 25. It will be noted that the gear 42 is non-rotatably secured to a stub shaft 44 at the gear hub 45. The stub shaft is threaded secured to a hollow driven shaft 46, the hollow driven shaft being rotatably mounted in bearings 47 and 48 in a boss 49 on the lower side of the casing 10.

The housing 12 is provided with a head 50 by means of which the housing is non-rotatably mounted upon the hollow driven shaft 46 by reason of interposition of a key 51.

The wall of the housing 12 provides a closed gear pocket 52 hermetically sealed by application of cap screws 53 which mount the head 50 on the housing. From the foregoing explanation it will become evident that when the power source 11 is operated and the clutch 35 is engaged, the power source acts through the drive shaft 26. The gears within the casing 10, and the driven shaft 46 will rotate the housing 12 and the blades which are mounted thereon.

In the chosen embodiment of the invention the housing 12 is provided with horizontally extending bosses 60, three in number, to accommodate the blade assemblies 13, 14 and 15. An inner blade shaft 61 is mounted at an inner end 62 rotatably in the wall of the casing and at another apertured end 63 is rotatably mounted within the boss 60. An outer blade shaft 64 is non-rotatably secured to the inner blade shaft by means of a key 65. Packing 66 retained by a packing nut 67 seals the gear pocket 52 where the blade shafts emerge.

On each of the outer blade shafts 64 is a combination troweling and servicing blade 68 secured to and below the respective blade shafts by means of brackets 69. Adjusting screws 70 and 71 extending through the blade shafts 64 and into the bracket 69 may be employed to secure the blade to the blade shafts and to adjust it in place. Gears 57 and 58 on their respective shafts 61 mesh with a gear 59 on the shaft 61 so that on tilting all will tilt in the same relative direction in response to an appropriate adjusting device.

For lubricating the gears and pinions which lie within the chamber 25 and interconnect the drive shaft 26 and hollow driven shaft 46 there is provided a bath of lubricating liquid which is adapted to fill the well 43 and if need be a portion of the chamber 25 above the top 75 of the well. Since the chamber is hermetically sealed,

there is no need to add lubrication from time to time. The lubricating fluid at the same time serves as a hydraulic fluid in a hydraulic pump and motor system employed to adjust the tilt of the blade assemblies 13, 14 and 15. To provide a source of hydraulic liquid under pressure there is employed a reciprocating hydraulic pump 75 mounted in the chamber 25 by means of a bracket 76 secured to the inside of the chamber wall. The pump 75, as best illustrated in Figure 4, has a pump chamber 77 and a pump rod 78 reciprocatably mounted therein. The pump rod has a head 79 engaged by a roller 80 of a walking beam 81. The beam is pivotally mounted by means of a shaft 82 upon the bracket 76. To give the motion needed to the walking beam 81 in order to reciprocate the pump rod 78 the clutch wall 37 previously referred to is eccentrically shaped so that an outer surface 83 is eccentric with respect to the axis of rotation and when the surface 83 is rotated in contact with a roller 84 on the walking beam, the walking beam will be rocked once in each direction for each rotation of the large gear 30. This action reciprocates the pump rod 78 and causes the pumping action in the pump 75.

A pump intake line 84 has an inlet 85 located in the well 43 and incidentally at a position adjacent the top surface of the pinion 40. The intake line 84, as illustrated in Figure 7, is directed past a ball check 86 into the pump chamber 77. As the pump rod 78 reciprocates from left to right, as viewed in Figure 7, liquid is drawn into the pump chamber. When the pump rod 78 moves from right to left, as viewed in Figure 7, the ball check 86 is seated and hydraulic liquid, which is also incidentally the lubricating liquid, is forced past a ball check 87 into and through a hydraulic power line 88 to a three-way valve 89. Interior details of the three-way valve 89 are illustrated in Figures 4 and 5.

The three-way valve is of substantially conventional construction and is adapted to the needs of the device here under consideration. The valve consists of a valve body 90 secured by appropriate conventional means to the wall of the chamber 25 near the side of the chamber to which the handle assembly 16 is attached. The body provides a valve chamber 91 within which a valve element 92 is adapted to reciprocate and to occupy any one of three different positions. In one operative position of the valve hydraulic liquid under pressure from the power line 88 travels through an inlet branch 93 to the valve chamber 91. It can be assumed that for the purpose of description the valve element 92 is in neutral position, namely, the solid line position of Figure 5. The inlet opening, not shown, for the inlet branch 93 is so positioned with respect to a reduced portion 94 on the valve element that hydraulic liquid under pressure will be by-passed upwardly and outwardly through a by-pass line 95 which is so positioned that it leads the by-pass liquid to a location above the top of the gear train so that while the liquid is being by-passed it is drained over the gears and pinions for the purpose of lubrication.

When, for example, the hydraulic liquid is to be used for adjusting the tilt of the blades, the valve element 92 may be set in a position nearest the left end of the valve chamber to which position it may be moved by operation of a valve lever 100 from the solid line position of Figure 5 to a broken line position 100' thereof. When the valve element is in the position last defined, hydraulic liquid under pressure from the hydraulic power line 88 and inlet branch 93 will be directed to a hydraulic line 101 which connects to a fitting 102 by means of which, as shown in Figure 6, hydraulic liquid under pressure can be passed through a passage 103 into a chamber 104 of a hydraulic motor. In addition to the chamber 104 which in effect is the interior of the hollow driven shaft 46 the motor consists of a piston 105 reciprocatably mounted in the chamber 104 to which is attached a piston rod 106 which extends downwardly in sliding relationship through a sleeve 107 into the gear pocket 52.

Because of the fact that the hydraulic motor comprising the parts just described must rotate with the driven shaft and the housing 12, the fitting 102 previously described must be a rotary fitting suitably constructed and packed in accordance with accepted practices and such that a portion 102' extending downwardly is rotatably mounted in a bearing 102" and the portion of the fitting connected to the hydraulic line 101 may as a consequence remain in fixed position while the shaft 44 and gear hub rotate.

Details of the hydraulic motor parts just described are best illustrated in Figure 6. As there shown the piston rod 106 has a crank 110 attached to its lower end.

On the lower end of the crank is a stub shaft 111 rotatably secured to the crank and having a pin 112 fastened to the stub shaft, the pin being non-rotatably mounted in the blade shaft element 64 in an angular direction as illustrated in Figure 6. As the piston 106 moves up and down, the blade shaft 64 will be rotated a corresponding amount and, in the example illustrated in Figure 6 by the broken line position, when the piston rod is moved downwardly so that the crank occupies the broken line position 110', the blade 68 will be tilted to the broken line position 68'. This is a considerable degree of tilt and would be an adjustment adapted for troweling. It will be clear from the foregoing explanation of operation of the hydraulic circuit that hydraulic power generated by the pump 75 when the motor or power source is in operation can be directed by manipulation of the three-way valve so that liquid flowing into the motor chamber 104 can force the piston head 105 downwardly, thereby forcing the piston rod 106 downwardly to make the adjustment just described. The downward force will tend to build up tension in a spring 113 so that when hydraulic pressure is released the spring will assist in returning the piston rod 106 and piston head 105 upwardly aiding the tendency of the force of material against the blades 68 to tilt the blade and cause a similar movement upwardly of the piston rod 106. Interconnection of pinions 57, 58 and 59 causes all blades to rotate simultaneously to the same extent. Further details of the blade adjustment are shown in Patent No. 2,468,981.

To release the blades for return to initial position the lever 100 is moved from the broken line position 100' to the broken line position 100", as illustrated in Figure 5. This causes the valve element 92 to shift from left to right to the end of its stroke. At the end of its stroke the valve element makes contact between a hydraulic return line 114 leading from the fitting 102 to the valve chamber 91. Fluid from the return line is passed through the chamber 91 to the by-pass line 95 and thence over the gears and pinions in the manner previously described. For convenience in valving when the blades are not being adjusted and the hydraulic system is running idling, the power line 88 may be directed through an idler branch 115 and thence through the by-pass line 95. This by-passing may also be operated if preferred simultaneously with the by-passing of return fluid from the hydraulic motor through the return line 114.

For manipulating the three-way valve there is provided a valve control lever 116. Normal or idler position of the hydraulic system is in effect when the valve control lever 116 is in the solid line position illustrated in Figure 5. The control lever is immediately adjacent a crossbar 117 of the handle assembly so that the blade adjustment can be made by thumb or finger pressure upon the control lever at any time. The control lever is pivotally mounted by means of a pin 118 in a shaft 119 of the handle assembly. A lower end 120 of the control lever is connected by means of a toggle 121 to a cable 122, which cable runs through a packing gland 123 to a toggle 124 by means of which it is attached to the lever 100.

So that the hydraulic system may not be overloaded with pressure at high speeds of rotation of the source of power there is provided a relief valve 125, as illustrated in Figure 7, spring loaded so that excess pressure will cause hydraulic fluid to be relieved through a neck 126 as long as the excess pressure prevails.

The clutch element 38 previously referred to is manipulated by a clutch lever 130 mounted adjacent and in front of the crossbar 117. A bracket 131 may be provided for mounting the clutch lever on the handle shaft 119. The clutch lever 130, as best illustrated in Figure 9, is provided with a composite pivotal mounting so that a slight movement of the clutch lever by the exertion of relatively little hand pressure is capable of being multiplied a suitable extent through a linking lever 132, whereby the movement is transferred through a toggle 133 to a clutch cable 134 which passes through an appropriate packing gland in the casing, not shown, to a position where, as shown in Figure 3, the clutch cable connects to a clutch control 135. The clutch control includes a clutch control shaft 136 which is rotated by reciprocation of the clutch cable 134, thereby to rotate a clutch eccentric 137 in a direction such that pressure is exerted upon a plate 138 when the clutch is to be disengaged and released from the plate when the clutch is to be engaged. As shown in Figure 1, a clutch spring 139 tends to raise the plate 138 and a sleeve 140, thereby to elevate the cone clutch element 38 moving it into engagement with the cone clutch face 36. For disengagement a spring 141 tends to rotate the clutch control shaft 136 in an opposite direction causing the eccentric to press upon the annular plate 138, thereby to disengage the clutch. A short link 142, not referred to previously in connection with manipulation of the clutch lever 130, makes possible the delicate movement of the clutch lever to engage and disengage the clutch without apparent effort on the part of the operator. Although a mechanical control has been shown and described for the clutch it will be appreciated that other power means such as a hydraulic control may be substituted.

To further facilitate operation of the device a throttle control or gas control lever 145 is mounted on the end of the handle shaft 119 immediately adjacent the valve control lever 116. The throttle control lever lies adjacent a crossbar 146 so that it can be readily operated by the thumb or fingers of the left hand of an operator as it rests upon the crossbar 146.

Circumstances may arise where it may be desirable to employ a hand operated hydraulic power system for adjusting the position of the blades. As shown in Figures 11 and 12 this may be accomplished by locating a hand actuated pump 150 in the handle shaft adjacent the crossbar 117. The pump may be supplied with a pump handle 151 pivotally mounted on a bracket 152 in the same relative location as the valve control lever 116 previously described. The pump may comprise a barrel 153 forming a pump chamber 154 within which a pump rod 155 is reciprocatably mounted. Packing 156 is supplied for the inner end of the rod sufficient to make a seal. When hydraulic liquid under pressure is to be supplied to the same motor previously described, the pump handle 151 is reciprocated. As the pump rod 155 is moved from right to left, as viewed in Figure 12, fluid is drawn inwardly from a reservoir 170 located in the handle, through a passage 171, and then through an inlet 157 past a check valve 158 into the chamber 154. When the rod is moved from left to right, as viewed in the same figure, the ball check 158 will seat and oil will be forced past a ball check 159 through an outlet passage 160 through an oil pressure supply line 161 to the fitting 102. The pump handle can be pumped as much as needed to tilt the position of the blades a desired amount. Pressure applied to the chamber 104 acts against the piston 105 and against the tension in the spring 113 in the same manner as previously described.

When the tilt of the blades is to be adjusted to a lesser degree, a release valve 165 is unseated by rotation of a valve handle 166 which will permit built-up pressure in the passage 160 to be relieved past a ball check 167 to a release passage 168.

Occasions may arise where it becomes undesirable to employ the gear system shown and described in connection with Figures 1 and 2. In such event a belt driven drive train may be employed, as illustrated in Figure 10. The belt drive train may be used in the same casing 10 which is used for the gear train. As shown there is connected to the drive shaft 26 a pulley 175 over which a V-belt 176 is passed in a suitable groove 177. The V-belt connects with a large pulley 178 provided with a similar groove 179. Rotation of the pulley 178 is passed through the clutch 35 in the same manner as previously described whereafter a pulley 180 keyed to the shaft 31 in place of the pinion, previously described, receives a belt 181 in a groove 182. The belt 181 transfers power to a large pulley 183 provided with a suitable groove 184 to receive the belt. The large pulley 183 in turn is keyed to the shaft 144 by means of a key 185. The shaft 144 is the same shaft as has already been described and from this point on the structure of the belt driven form of the device is the same as has been described heretofore.

When the belt drive is employed as described in connection with Figure 10, the bath of lubricating fluid must be omitted. In that event the hydraulic system initially described, which depends upon the reservoir of lubricating fluid for a supply of hydraulic fluid, need be omitted. Consequently for the belt driven form of the device the hand operated hydraulic system for adjusting the tilt of the blades is preferable by making use of a separate reservoir such as the reservoir 170.

In the operation of machines of the type herein described it is highly advantageous to be able to readily lift the device to move it from one location to another. To facilitate such a lifting operation a hole 190 is provided on the side of the lower casing half 23 opposite from the side to which the handle is attached. A lifting bar 191, a fragmentary portion of which is illustrated in Figure 1, is adapted to be inserted into the hole 190 and by use of the lifting bar in conjunction with use of the handle in its lowermost position two operators can readily lift the entire apparatus. The lifting bar may for convenience be carried by brackets 194 on the handle 16.

Conditions also arise where a machine of greater spread may be better able to perform a desired surfacing operation in some particular type of installation. The design and construction herein described enables use of the machine as either a three-foot diameter machine or a four-foot diameter machine. When equipped initially as a three-foot machine, those changes necessary comprise substitution of a four-foot diameter ring guard for the original ring guard and replacement of the original blades 68 with corresponding longer blades. The blade fittings such as the inner shaft 61 and the gears may remain the same. When the machine of larger diameter is desired, a greater weight may be necessary. Weight can be added to the casing by attaching to the opposite long sides of the casing additional weights. No other change in the apparatus is necessary. Consequently the same apparatus can be used as either a high horse-power or low horse-power machine.

To attach the weights there are provided platforms 192 which may be provided with apparatus 193 adapted to the reception of lead weights or weights of corresponding character which may be snugly held near the center of gravity of the machine, thereby to increase the weight of the machine to give greater stability when higher power is employed.

Should an occasion arise when a power source of different performance might be desirable, only the power source, the drive shaft 26 and pinion 28 need be removed.

for substitution of a heavier or a lighter power source with a similar drive shaft and pinion.

There has accordingly been described herein a compact, effective, rotary finishing machine, moving parts of which are well protected and concealed and which by reason of the mechanical structure involved is safe to operate and easy to manipulate from the operating handle. The device is sensitive to adjustment so that it can be readily set at a desired troweling adjustment, in which adjustment the speed can be carefully controlled and readily shut off.

While we have herein shown and described our invention in what we have conceived to be the most practical and preferred embodiment, it is recognized that departures may be made therefrom within the scope of our invention, which is not to be limited to the details disclosed herein but is to be accorded the full scope of the claims so as to embrace any and all equivalent devices.

Having described our invention, what we claim as new and desire to secure by Letters Patent is:

1. A rotary machine for surfacing concrete comprising a casing forming a chamber, a guard extending below the casing, a driven shaft extending below the casing, a housing attached to the driven shaft beneath the casing, and a handle on the casing, a power plant mounted on the casing and a drive shaft from the power plant extending into the casing, a power train in the chamber interconnecting the drive shaft and the driven shaft, a plurality of surfacing blades extending radially outwardly from said housing and tiltably mounted on longitudinal axes thereof in said housing and a tilting means interconnecting said blades adapted to alter the adjustment of said blades, said casing including a reservoir of hydraulic liquid associated with the machine, a pump on the machine and in said casing connected to said reservoir, a pump driving mechanism operably connected between said power train and the pump, a hydraulic motor on the machine having a connection to said tilting means adapted to effect a tilt adjustment in said blades, a hydraulic valve on the machine connected to said pump, a hydraulic connection from said valve to said hydraulic motor, a hydraulic pressure release connection from said valve to said reservoir, and a hydraulic return connection to said reservoir from said valve adapted to discharge hydraulic liquid from said motor.

2. A rotary machine for surfacing concrete comprising a casing forming a chamber a hollow driven shaft extending below the casing, a housing attached to the driven shaft, and a handle extending laterally outwardly and upwardly from the casing, a power plant mounted on the casing and a drive shaft for the power plant extending into the casing, a power train in the chamber interconnecting the drive shaft and the driven shaft, a plurality of surfacing blades extending radially outwardly from said housing and tiltably mounted on longitudinal axes thereof in said housing and tilting means interconnecting said blades adapted to alter the adjustment of said blades, said casing including a reservoir of hydraulic liquid associated with said chamber, a pump carried by the casing connected to said reservoir, a pump driving mechanism operably connected between said power train and the pump, a hydraulic motor in the driven shaft connected through said driven shaft to said tilting means adapted to effect a tilt adjustment in said blades, a hydraulic valve carried by the casing connected to said pump and having a manual control therefor on said handle, a hydraulic connection from said valve to said hydraulic motor, and a hydraulic return connection to said reservoir from said valve adapted to discharge hydraulic liquid from said motor.

3. A rotary machine for surfacing concrete comprising a casing having upper and lower halves forming a sealed chamber, an annular guard extending below the casing, a driven shaft bushing on the lower side of the casing having a hollow driven shaft mounted therein, a gear

housing attached to the driven shaft beneath the bushing, and a handle extending laterally outwardly and upwardly from the casing, a power plant mounted on the casing and a drive shaft for the power plant extending into the casing, a speed reducing power train in the chamber interconnecting the drive shaft and the driven shaft and having an element thereof on the upper end of the driven shaft, a plurality of concrete surfacing blades extending radially outwardly from said housing and tiltably mounted on longitudinal axes thereof in said housing and a gear train for said blades interconnected in said housing including means adapted to alter the adjustment of said blades, said chamber comprising a reservoir for hydraulic liquid, said means comprising a reciprocating pump in the chamber connected to said reservoir, a pump driving mechanism operably connected between said power train and the pump, a hydraulic motor mounted in the driven shaft and connected through said driven shaft to said gear train, said hydraulic motor having a connection to the blades and adapted to effect a tilt adjustment in said blades, a three-way hydraulic valve in the chamber connected to said pump and having a manual control therefor on said handle, a hydraulic connection from said valve to said hydraulic motor, a hydraulic release connection from said valve to said reservoir, and a hydraulic return pressure connection to said reservoir from said valve adapted to discharge hydraulic liquid from said motor, a clutch in said chamber between the drive shaft and the driven shaft, said clutch being operatively connected with the speed reducing power train, and clutch operating means on said handle operatively connected to said clutch adapted to engage and disengage said clutch at any time.

4. A rotary concrete surfacing machine comprising a casing forming a chamber, a power plant on said casing having a drive shaft extending into the casing, a bearing on the lower side of the casing having a hollow driven shaft rotatably mounted therein, a gear train in said chamber including rotating elements connecting said drive shaft and said driven shaft and a clutch comprising one of said rotating elements in said gear train, means forming a reservoir in the lower part of said chamber for a supply of hydraulic liquid, a reciprocating hydraulic pump connected to said supply and a rotating eccentric cam mounted upon one of said rotating elements the gear train in operating relation with said pump, a hydraulic valve device in said chamber connected to said pump and a valve element in the valve device, a by-pass line from said valve device directed over said gear train for discharging hydraulic liquid to lubricate said train, a housing mounted on a lower end of said driven shaft, blades rotatably mounted on said housing on longitudinal axes thereof and in radially outwardly extending position, tilting means on said blades in said housing extending radially outwardly of the axes of the blades and a common vertically moving adjusting drive for said tilting means, a hydraulic motor in the casing, a connection from said motor to said tilting means, a hydraulic power connection from said valve device to said motor, and a hydraulic release connection in said valve device from said motor to said by-pass line.

5. A rotary concrete surfacing machine comprising a casing forming a chamber, a power plant on said casing having a drive shaft extending into the casing, a bearing on the lower side of the casing having a hollow driven shaft rotatably mounted therein, a speed reducing gear train in said chamber connecting said drive shaft and said driven shaft and a clutch in said gear train, means forming a reservoir for a supply of hydraulic liquid in the lower part of said chamber, a reciprocating hydraulic pump connected to said supply and a rotating eccentric cam in the gear train in operating relation with said pump, a three-way hydraulic valve device in said chamber connected to said pump and a three position valve element in the valve device, a by-pass line from said valve device directed over said gear train for discharging hy-

draulic liquid to lubricate said train, a gear housing mounted on said driven shaft, blades rotatably mounted on said housing on longitudinal axes thereof and in radially outwardly extending position, gears on said blades in said housing and a common vertically moving adjusting drive for said gears, a hydraulic motor in the hollow driven shaft connected through the driven shaft to said adjusting drive and a hydraulic connection from said valve device to said motor, a hydraulic release connection in said valve device from said motor to said by-pass line, a handle on the casing, operating means on the handle connected to said valve element, and a separate operating means on the handle connected to said clutch.

6. A rotary machine for surfacing concrete comprising a casing having a closed chamber therein, said casing having an upper side and a lower side, a power plant mounted on said upper side, a hollow driven shaft mounted on said lower side in general alignment with said power plant and a housing at the lower end of said shaft having a closed pocket therein, radially positioned blade assemblies tiltably mounted on said housing and extending into said pocket, a common tilting means for said blades extending from said blades into said shaft, a drive train in said chamber having a connection to said power plant and having a connection to said shaft within said chamber, a clutch having an operative connection between opposite ends of said drive train and mounted within said chamber, a hydraulic pump, pump actuating means operatively connected between said drive train and said pump, and a hydraulic motor carried by said shaft in axial alignment therewith and operatively connected to said tilting means, and controls respectively for said clutch and said hydraulic motor mounted exterior to said casing.

7. A rotary machine for surfacing concrete comprising a casing having a closed chamber therein, said casing having an upper side and a lower side, a power plant mounted on said upper side having a throttle therefor, said power plant having a closed junction with said chamber, a hollow driven shaft mounted on said lower side in general alignment with said power plant and a housing at the lower end of said shaft having a closed pocket therein, radially positioned blade assemblies tiltably mounted on said housing and extending into said pocket, a common tilting means for said blades extending from said blades into said shaft, a drive train in said chamber having a connection to said power plant in said closed junction and having a connection to said shaft within said chamber, a clutch operatively connected between opposite ends of said drive train and mounted within said chamber, a hydraulic pump carried by the casing in said chamber and a pump actuating means operatively connected between said drive train and said pump, a hydraulic motor carried by said shaft in axial alignment therewith and operatively connected to said tilting means, a handle on the casing and controls on the handle connected respectively to said clutch, said hydraulic motor and said power plant control.

8. A rotary machine for surfacing concrete comprising a casing forming a closed chamber, a power plant on the casing having a drive shaft extending into the chamber, a hollow driven shaft rotatably mounted in the chamber at the lower side of the casing, a drive train between the drive shaft and the driven shaft, a housing below the casing mounted on said driven shaft for rotation thereby, a plurality of blades extending radially outwardly from the housing and having an adjustable tilttable mounting thereon, tilting means in the casing secured to the blades, a common adjusting element interconnecting said blades and having an actuator extending through said driven shaft into said casing, said actuator comprising an axial chamber in the driven shaft, a piston reciprocatably mounted in the axial chamber and a piston rod thereon in operating engagement with said tilting means, a fluid

passage from said axial chamber through the upper portion of the driven shaft and terminating at the upper end thereof, a fluid connection swivelly mounted at the upper end of the driven shaft in communication with said fluid passage, an operating handle on the casing having a hand hold thereon, a fluid pump on the operating handle, an actuating handle connected to the pump and movably mounted on the operating handle adjacent said hand hold, and a fluid line having a relatively fixed location, one end of said line having a stationary connection to the pump and the other end of said line having a connection to the fluid fitting at a fixed location within the chamber, and a manual release fluid return in the fluid line located on the operating handle.

15 9. A rotary machine for surfacing concrete comprising a casing forming a closed chamber, a power plant on the casing having a drive shaft extending into the chamber, a hollow driven shaft rotatably mounted in the chamber at the lower side of the casing, a drive train between the drive shaft and the driven shaft, a housing below the casing mounted on said driven shaft for rotation thereby, a plurality of blades extending radially outwardly from the housing and having an adjustable tilttable mounting thereon, tilting means in the casing secured to the blades, a common adjusting element interconnecting said blades and having an actuator extending through said driven shaft into said casing, said actuator comprising an axial chamber in the driven shaft, a piston reciprocatably mounted in the axial chamber and a piston rod thereon in operating engagement with said tilting means, a fluid passage from said axial chamber through the upper portion of the driven shaft and terminating at the upper end thereof, a fluid connection swivelly mounted at the upper end of the driven shaft in communication with said fluid passage, an operating handle on the casing having a hand hold thereon, a fluid pump on the operating handle, an actuating handle connected to the pump and movably mounted on the operating handle adjacent said hand hold, and a fluid line having a relatively fixed location, one end of said line having a stationary connection to the pump and the other end of said line having a connection to the fluid fitting at a fixed location within the chamber, and a manual release fluid return in the fluid line located on the operating handle, a clutch in said drive train and within said closed chamber, said clutch having a pair of relatively movable clutch halves, a clutch actuating lever on the operating handle adjacent said hand hold, and a connection from the clutch actuating lever extending through said operating handle to one of said clutch halves whereby to enable actuation of the clutch at the same relative location as that occupied by the actuating handle.

40 10. A rotary machine for surfacing concrete comprising a casing forming a chamber, a hollow driven shaft extending below the casing, a housing attached to the driven shaft, and handle extending laterally outwardly and upwardly from the casing, a power plant mounted on the casing and a drive shaft for the power plant extending into the casing, a power train in the chamber interconnecting the drive shaft and the driven shaft, a plurality of surfacing blades extending radially outwardly from said housing and tiltably mounted on longitudinal axes thereof in said housing and tilting means interconnecting said blades adapted to alter the adjustment of said blades, said casing including a reservoir of hydraulic liquid associated with said chamber, a pump carried by the casing connected to said reservoir, a pump driving mechanism operably connected between said power train and the pump, an axial chamber in the driven shaft, a hydraulic motor in the axial chamber connected through said driven shaft to said tilting means adapted to effect a tilt adjustment in said blades, a hydraulic valve carried by the casing connected to said pump and having a manual control therefor on said handle, a hydraulic connection from said valve to said hydraulic motor, and a hy-

draulic return connection to said reservoir from said valve adapted to discharge hydraulic liquid from said motor, a bracket element on the casing for said handle, a complementary bracket element on the handle, a series of apertures respectively on said bracket element having a plurality of positions of alignment, and a pin engageable with aligned apertures in each of said plurality of positions of alignment.

11. A rotary machine for surfacing concrete comprising a casing forming a chamber, a hollow driven shaft extending below the casing, a housing attached to the driven shaft, and a handle extending laterally outwardly and upwardly from the casing, a power plant mounted on the casing and a drive shaft for the power plant extending into the casing, a power train in the chamber interconnecting the drive shaft and the driven shaft, a plurality of surfacing blades extending radially outwardly from said housing and tiltably mounted on longitudinal axes thereof in said housing and tilting means interconnecting said blades adapted to alter the adjustment of said blades, said casing including a reservoir of hydraulic liquid associated with said chamber, a pump carried by the casing connected to said reservoir, a pump driving mechanism operably connected between said power train and the pump, an axial chamber in the driven shaft, a hydraulic motor in the axial chamber connected through said driven shaft to said tilting means adapted to effect a tilt adjustment in said blades, a hydraulic valve carried by the casing connected to said pump and having a manual control therefor on said handle, a hydraulic connection from said valve to said hydraulic motor, and a hydraulic return connection to said reservoir from said valve adapted to discharge hydraulic liquid from said motor, a guard ring surrounding outer ends of said blades, said ring comprising separable substantially semicircular halves and releasable connections between ends of said halves, legs on each said half and releasable connections between said legs and the casing mounting said ring below the casing at a location adjacent the outer ends of said blades.

12. A rotary concrete surfacing machine comprising a casing forming a chamber, a power plant on said casing having a drive shaft extending into the casing, a bearing on the lower side of the casing having a driven shaft rotatably mounted therein, a gear train in said chamber including rotating drive elements and rotating driven elements connecting said drive shaft and said driven shaft and a clutch in said gear train interconnecting said drive elements and said driven elements when engaged, a part of said chamber forming a reservoir for a supply of liquid, a reciprocating hydraulic pump connected to said reservoir, one of said rotating drive elements having a periph-

eral cam face, a lever pivotally mounted between said pump and said cam face to reciprocate the pump while said cam face is rotating, a hydraulic valve device connected to said pump and a valve element in the valve device having a manually operating element extending outside said casing, a housing mounted on said driven shaft, blades tiltably mounted on said housing on longitudinal axes thereof and in radially outwardly extending position, tilting means on said blades extending radially with respect to the axes, a common adjusting drive for said tilting means and a reciprocating hydraulic motor having a hydraulic liquid supply connection to said valve device and a mechanical output element on said last named hydraulic motor operatively connected to said tilting means.

13. A rotary concrete surfacing machine comprising a casing having a chamber therein, a power source carried by the casing, a concrete surfacing means comprising a housing, a hollow driven shaft fixed to said housing and rotatably mounting the same on the casing and a set of horizontally rotating blade assemblies separately rotatably mounted on horizontal axes on the housing and extending radially outwardly therefrom, a tilt adjusting means having a portion thereof in the housing common to all said blade assemblies and in operable engagement with said blade assemblies, said tilt adjusting means having a portion thereof extending through the hollow driven shaft into said chamber, a gear train including rotating drive means operatively connected to the power source and rotating driven means operatively connected to the hollow driven shaft and a clutch connecting said rotating driven means when engaged, a separate actuator operatively connected to said tilt adjusting means, a power take-off operatively connected to said rotating drive means, and a manually operable blade tilting control device arranged to selectively connect said power take off to said actuator whereby to effect selective power-actuated adjustment of said blades independently of rotation of said hollow driven shaft and at the will of the operator.
